(57) **CLAIM**

The ornamental designs for a can dispenser rack for refrigerator door, as shown and described.

DESCRIPTION

FIG. 1 is a front perspective view of a transparent can dispenser rack for refrigerator door showing our new design;
FIG. 2 is a rear perspective view thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a top view thereof;
FIG. 8 is a bottom view thereof; and
FIG. 9 is a front perspective view thereof showing environment.

FIG. 10 is a front perspective view of an opaque can dispenser rack for refrigerator door of our new design;
FIG. 11 is a rear perspective view of the second embodiment;

FIG. 12 is a front elevation view of the second embodiment;
FIG. 13 is a rear elevation view of the second embodiment;
FIG. 14 is a right side elevation view thereof;
FIG. 15 is a left side elevation view thereof;
FIG. 16 is a top view thereof;
FIG. 17 is a bottom view thereof; and,
FIG. 18 is a front perspective view thereof showing environment.

In FIGS. 1 through 8, and FIGS. 10 through 17, the broken lines are for the purpose of illustrating portions of the can dispenser rack for refrigerator door that form no part of the claimed design. In FIGS. 9 and 18, the broken lines are for the purpose of showing the environment of the can dispenser rack for refrigerator door that form no part of the claimed design.
